GUN MOUNT

Original Filed April 10, 1928 2 Sheets-Sheet 2

UNITED STATES PATENT OFFICE

REX B. BEISEL, OF TULSA, OKLAHOMA, ASSIGNOR TO CURTISS AEROPLANE & MOTOR COMPANY, INC., A CORPORATION OF NEW YORK

GUN MOUNT

Refiled for abandoned application Serial No. 268,907, filed April 10, 1928. This application filed April 3, 1930. Serial No. 441,357.

This application is a refile of my former application, Serial Number 268,907.

My invention relates to gun mounts and more particularly to gun mounts for aircraft.

8 An object of the invention is to provide a gun mount for aircraft in which the usual adjustment of the gun carriage is obtained by foot or pedal action rather than by hand as heretofore.

10 A further object of the invention is to provide a gun mount for aircraft in which the adjusting pedals are movable both with and

15 with respect to the gun carriage either independently or simultaneously, the movements in one instance being such that the gun carriage is vertically adjusted and in the other instance such that it is adjusted or rotated horizontally.

20 A still further object of the invention is to provide an auxiliary pedal arrangement whereby the adjusting mechanism, and hence the gun carriage, can be locked and released as desired.

25 The advantages of a gun mount thus characterized are as follows: No hand manipulation of the gun mount is under any circumstances required. The gunner can, while seated, freely adjust the gun mount both vertically and horizontally. This is equivalent

30 to adjusting the gun mount in elevation, and in azimuth respectively. With one continuous motion the adjusting mechanism can be released and the gun carriage adjusted. The

35 return of the lock mechanism into locking engagement is instantaneous and automatic the moment pressure on the lock release pedal is removed. The adjusting pedals offer at all

40 times a solid foot rest against which the gunner's feet are firmly braced. It becomes unnecessary for the gunner to stand erect or to expose his head or shoulders above the top of the body of the machine. Moreover, as

45 only a very insignificant portion of the gun mount is exposed, little or no resistance is offered thereby during flight. Such, and other advantages, result from the use of a gun mount of the character herein set forth.

50 In the drawings, wherein like reference

characters denote like or corresponding parts,

Fig. 1 is a side elevation of a standard type of military aeroplane having installed thereon a gun mount of the type herein disclosed;

55 Fig. 2 is a plan view of the machine illustrated in Fig. 1;

Fig. 3 is a side elevation of the gun mount; the adjacent portion of the aeroplane fuselage or body being shown in section;

60 Fig. 4 is a front elevation, partly in section, of the structure illustrated in Fig. 3; and

Fig. 5 is a plan view of the adjusting and lock release mechanism.

65 In the embodiment of the invention selected for illustration, a military aeroplane of more or less conventional design is shown. Such aeroplane includes the usual fuselage or body

10, supporting surfaces 11—11, empennage 70 12, power plant 13, and landing gear 14.

Within the body 10 two cockpits are provided. Said cockpits are designated respectively as 15 and 16. To shield the occupant

of the cockpit 16 a wind shield 17 is provided. Within the cockpit 16 the gun mount

designated in its entirety as 18 is fastened. As indicated in Figs. 3 to 5, inclusive, the

gun mount 18 consists of a rotatable up-right member 19 carried at one end above and be-

yond the cockpit coaming, to which extended end, the gun carriage 20 is pivotally fastened as at 21. The gun carriage 20 is provided at

75 its forward end with a collar 21 to which the machine gun, designated in its entirety as 22, is mounted for free swinging movement both vertically and horizontally. The upright member 19 is carried throughout a substantial portion of the depth of the fuselage or body

10. At its upper end it is mounted in a bearing 23 fastened to the fuselage frame. At its lower end it is mounted in a bearing 24 similarly fastened to the fuselage frame. Inter-

mediately of its ends it is mounted in a bearing 25 provided at the upper end of a sleeve

26 carried along a substantial portion of the length of the up-right member from a point at or near its lower end. This sleeve 26 is

non-rotatable. It has keyed thereto as at 27 a vertically slidable bevel gear 28. The func-

100

tion of this gear 28 is that of a lock rather than a gear. The manner in which this gear 28 is adapted to engage with gear segments 29-29 will be hereinafter set forth.

5 At or near its lower end the up-right member 19 has pinned thereto as at 30 two oppositely extending pedal arms 31. Each arm 31 has mounted thereon an operating pedal 32 shaped at its free end as at 33 to comfortably receive the feet of the gunner. With the pedals released, the gunner can, by exerting pressure on one or the other of the pedals 32, rotate the up-right member 19, and hence the gun carriage 20, as desired.

15 The pedals 32 are mounted to move not only with but also with respect to the arms 31. That the latter movement may be obtained, each pedal 32 is provided at its lower end with a sleeve 33^a thru which the arms 31 are carried. The inner leg of each pedal 32, it will be noted, extends beyond its associated sleeve 33^a. Such extended portion, designated as 34, provides in effect a bell crank extension. Each said extension at its forward end is pivotally fastened as at 35 to a rod connection 36 which, at its opposite end, is pivotally fastened as at 37 to the gun carriage of gun carrying arm 20. It is by means of this connection 36 that the gun carriage is vertically adjusted thru the rotational movement of the pedals 32 about the pedal arms 31 as an axis.

The lock release mechanism, in addition to the gear 28 and gear segments 29, includes 15 an auxiliary pedal 38 for each pedal 32 and a spring 39. The auxiliary pedals 38 are pivotally fastened as at 40 to the pedals 32 and have pivotally fastened thereto as at 41 links 42. At their opposite ends the links 42 are pivoted as at 43 to the arms 44 fastened to and extending off from a shaft 45 carried from one to the other of the pedals. This shaft 45 has fastened thereto a sleeve 46 provided with cams 47 by means of which, thru the operation of the auxiliary pedals 38, the gear 28 is raised out of mesh with the gear segments 29. The working face of each said cam 47 is described about the center of the pedal arms 31 as an axis. To release the adjusting mechanism it is only necessary that one or the other of the auxiliary pedals 38 be depressed. The spring 39, which encircles the sleeve 46, and which bears at its opposite ends on an annular flange 48 extending out from said sleeve and on the top face of the gear 28 respectively, acts to return the latter into meshing engagement with the gear segments 29 when pressure on the pedals 38 is removed. The gear segments 29, it will be noted, are fastened to the inner arms of the pedals 32 and by their engagement with the gear 28 lock the pedals 32 in that position of rotational adjustment desired. An arcuate slot 50 is formed in the cockpit coaming to admit of the passage of the connection 36 therethru

as well as its rotational movement with the up-right member 19.

As intimated, a gun mount thus characterized may be freely manipulated by the gunner while seated. To obtain horizontal adjustment of the gun mount it is but necessary to depress one or the other of the auxiliary pedals 38 until the cams 47 shall have raised the gear lock 28 out of engagement with the gear segments. With the gear segments thus released the pedal arms 31 may be rotated, or partially rotated, to correspondingly swing the up-right member 19 about its vertical axis. To adjust the gun, however, vertically, pressure may be exerted on the pedals 32 to rock or swing said pedals about the pedal arms 31 as an axis. Such movement of the pedals 32 will elevate the connection 36 and raise or lower the gun carriage 20 as desired.

170 Either or both said adjustments can be effected either simultaneously or separately as desired. As the gun carriage adjustment is obtained thru foot action alone, the gunner may use both hands in manipulating the gun 75 22 as desired.

175 While I have described my invention in detail in its present preferred embodiment, it will be obvious to those skilled in the art after understanding my invention, that various changes and modifications may be made therein without departing from the spirit or scope thereof. I aim in the appended claims to cover all such modifications and changes.

90 What I claim is:

1. A gun mount for aircraft including a gun carriage adjustable in rectangularly opposed planes in its relation to the aircraft, and unitary foot-operated mechanism associated with and by means of which the gun carriage is adjusted in either or both said planes. 100

105 2. In combination, an aerial vehicle, a cockpit comprising a gunner's compartment included therein, a gun carriage adjustable in rectangularly opposed planes in its relation to the aircraft and in relation to the gunner's compartment, unitary foot-operated mechanism associated with and by means of which the gun carriage is adjusted in either or both of said planes with reference to said compartment, and means for locking said gun carriage in its adjusted position fixedly relative to said compartment. 110

115 3. A gun mount for aircraft including a gun carriage adjustable in rectangularly opposed planes in its relation to the aircraft, a unitary foot-operated mechanism associated with and by means of which the gun carriage is adjustable in either or both said planes, and means operable to lock said adjusting mechanism and hence the gun carriage. 120

125 4. A gun mount for aircraft including an upright member, an adjustable gun carrying arm pivotally fastened to said member, foot-operated mechanism having an axis of rota- 130

- tion passing thru said member, and a connection extending between said mechanism and said arm substantially parallel with said member.
5. A gun mount for aircraft including a rotatable up-right member, a gun carrying arm movable with and adjustable in its relation to said member, an arm rigidly fastened to said member, said arm being movable with said member about an axis passing thru said member to rotate said gun carrying arm, and mechanism carried by said rigid arm and connected to said gun carrying arm for adjusting said last mentioned arm.
10. 6. A gun mount for aircraft including a gun carriage rotatable and vertically adjustable in its relation to the aircraft, foot-operated mechanism by means of which said carriage is both rotated and vertically adjusted, and foot-operated mechanism by means of which said first mentioned mechanism is locked and unlocked in its relation to said carriage.
15. 7. A gun mount for aircraft including a gun carriage both rotatably and vertically adjustable in its relation to the aircraft, a foot pedal movable both with and with respect to said gun carriage to respectively rotate and vertically adjust it as aforesaid, mechanism operable to lock and release said pedal, and an auxiliary foot pedal operable to actuate said lock mechanism.
20. 8. In combination, an aerial vehicle, a cockpit comprising a gunner's compartment included therein, a gun carriage adjustable in its relation to said aircraft and to said cockpit, a support for the gun carriage, foot-operated mechanism associated with and by means of which the gun carriage is adjusted, and means operable in its relation to said support to lock and release said mechanism.
25. 9. A gun mount for aircraft comprising an upright, a gun carrying arm associated with the upper part of said upright and arranged for rotational movement about the longitudinal axis of said upright and also for rotational movement about a normally horizontal axis substantially perpendicular to the first named axis, an operating arm associated with a lower part of said upright and also arranged for rotational movement about the longitudinal axis of said upright and for rotational movement about a normally horizontal axis perpendicular thereto, means for moving said operating arm about said two axes, and means for transmitting the motion of the operating arm to the gun carrying arm to cause corresponding movements thereof.
30. 10. A gun mount for aircraft comprising a normally upright member, a gun carrying arm carried thereby and mounted for rotational movement about a normally horizontal axis substantially perpendicular to the upright member, an operating arm also carried by the upright member which arm is also mounted for rotational movement about a normally horizontal axis substantially perpendicular to the upright member and is maintained substantially parallel to the gun carrying arm, a link connecting the two arms, and means for moving said operating arm to adjust the position of the gun carrying arm.
35. 11. A gun mount for aircraft including a gun carriage adjustable in elevation and in azimuth with respect to the aircraft, and unitary foot operated means horizontally and vertically rotatable to adjust the azimuth and elevation respectively of said gun carriage.
40. 12. A gun mount for aircraft including a gun carriage adjustable in elevation and in azimuth with respect to the aircraft, unitary foot operated means horizontally and vertically rotatable to adjust the azimuth and elevation respectively of said gun carriage, and unitary locking means adapted to lock said gun carriage in any position of adjustment.
45. 13. A gun mount for aircraft including a gun carriage adjustable in elevation and in azimuth with respect to the aircraft, unitary foot operated means horizontally and vertically rotatable to adjust the azimuth and elevation respectively of said gun carriage, unitary locking means adapted to lock said gun carriage in any position of adjustment, and an operating device for said locking means associated with said adjusting means.
50. In testimony whereof I hereunto affix my signature.
